HAIR DRYER

Marilyn Lucey, Pawtucket, R.I., assignor to Hasbro
Industries, Inc., a corporation of Rhode Island

Filed July 29, 1968, Ser. No. 12,946

Term of patent 7 years

Int. Cl. D23—03

U.S. Cl. D23—77

FIG. 1

FIG. 2

FIG. 3

FIG. 4

FIG. 5

FIG. 6

FIG. 1 is a front perspective view of a hair dryer showing my design in the position of use;

FIG. 2 is a top plan view of the bottom portion thereof with the hose and handle portions removed;

FIG. 3 is a top plan view of the top portion of the hair dryer;

FIG. 4 is a side elevational view thereof;

FIG. 5 is a rear elevational view thereof; and

FIG. 6 is a front perspective view of the hair dryer.

I claim:

The ornamental design for a hair dryer, substantially as shown.
